GEORG SAUBER, OF UERDINGEN-ON-THE-RHINE, GERMANY, ASSIGNOR TO THE FIRM
BÜTTNERWERKE, AKTIENGESELLSCHAFT, OF UERDINGEN-ON-THE-RHINE, GERMANY.

DRYING DRUM.

Application filed August 24, 1921. Serial No. 494,888.

To all whom it may concern:

Be it known that I, GEORG SAUBER, a citizen of the German Republic, residing at Uerdingen-on-the-River Rhine, Germany, have invented certain new and useful Improvements in Drying Drums (for which I have made applications as follows: Germany, Oct. 29, 1918; Austria, Nov. 20, 1919; Sweden, Nov. 5, 1919; Denmark, Nov. 21, 1919; Norway, Nov. 26, 1919; Holland, Nov. 19, 1919; Czechoslovakia, Dec. 23, 1919), of which the following is a specification.

There have already become known drying drums in which a set of chambers is formed by means of longitudinal partitions so that the material to be dried flows from one chamber into the other over the longitudinal edges of said partitions. According to another form of construction lifting blades are arranged upon the inner surface of the drum, the material to be dried being thus also lifted so that it drops upon the lower blades passing through the free inner space of the drum.

It has already been proposed to indent the edges of the blades and partitions to obtain a larger surface of contact between the material to be dried and the heating gases. In this manner the material to be dried is made to flow in cascades in thin sheets through the drum but only in the longitudinal direction so that between the different sheets of material remain free spaces through which the heating gases pass without effect upon the material. It has further been proposed to use the movement in cascades of the material to be dried in such drying drums where the heating gases flow in transverse direction through the drum, but in this case also a large part of the heating gases flows through the spaces between the cascades without being utilized.

This invention has for its object a construction of the drying drum which is improved so that no free spaces remain between the sheets of material in the direction in which the heating gases flow.

With this object in view the lifting blades or baffling plates have narrow transverse slots alternately arranged at short distances apart. When the material to be dried moves forward it flows through these slots in a direction perpendicular to the axis of the drum and in thin sheets so that disc-

like sheets are formed which together cover the cross section of the drum succeeding each other in multiple repetition so that the heating gases are forced to traverse these sheets of material. In this manner all the heating gases are fully utilized and a more economical working of the apparatus is obtained than with the apparatus of known construction.

In the accompanying drawing two forms of construction of the apparatus are shown by way of example in cross section and in longitudinal section, the direction of rotation being indicated by arrows.

Fig. 1 is a cross section of a drying drum embodying one form of the invention. Fig. 2 is a fragmentary longitudinal section on the line 2-2 of Fig. 1. Fig. 3 is a cross section of a drying drum embodying another form of the invention. Fig. 4 is a fragmentary longitudinal section of Fig. 3.

In the partitions of the drum according to the first form of construction and in the lifting plates of the drum according to the second form of construction slots *c* are arranged which stand transversely to the longitudinal direction of said partitions and plates. These slots succeed each other at short distances and each slot is comparatively small. Thus are formed the thin transverse sheets of material shown in the drawing which together cover the cross section of the drum; the material flows of course also over the longitudinal edge of the partitions or plates (cfr. at *a*).

In order to avoid great heights of fall and to ensure the careful treatment of material which is easily damaged it is advisable, particularly if partitions are used as shown in Figs. 1 and 2, to make the slots *c* in the partitions alternate (cfr. the longitudinal section). As shown in Figures 3 and 4 the lifting blades (cfr. *c'*) in different compartments alternate with regard to one another.

In open drums with single lifting blades upon the inner wall part of the upper cross section of the drum remains free of material to be dried, one part of the lower cross section being filled with material. In order to avoid that the heating gases flow through this free space of the drum without being utilized, several rings *d* of sheet metal are arranged, according to this invention, in the

annular space formed by the lifting blades, said rings do not make narrower the middle main passage within the ring formed by the lifting blades but they serve to prevent, 5 that considerable parts of the heating gases flow outside said annular space. It is however advisable to allow some part of the heating gases to flow through this outer space and for this reason the rings *d* are 10 not arranged in close proximity of the inner wall of the drum.

It will be understood that the rotatable drums embodying the forms of invention above described will be arranged at a slight 15 inclination to cause the material to travel from end to end thereof, as is customary in drums of this type.

I claim:—

1. An improved drying drum for the formation of thin sheets of material to be dried, comprising a rotatable drum having longitudinally arranged lifting members fixed therein, each of said members having a plurality of narrow transverse slots through 25 which the material flows in thin sheets at right angles to the direction in which the heating gases flow through said drum.

2. An improved drying drum for the formation of thin sheets of material to be dried, 30 comprising a rotatable drum having a plurality of lifting plates extending from the inner periphery thereof inwardly, each of said plates having a number of closely spaced transverse slots through which the

material flows in thin sheets at right angles 35 to the direction in which the heating gases flow through said drum.

3. An improved drying drum comprising a rotatable drum having a plurality of lifting members fixed to the inner periphery 40 thereof, said members being constructed and arranged to cause the material lifted thereby to flow in thin sheets at right angles to the direction in which the heating gases flow through said drum. 45

4. An improved drying drum with partitions or lifting blades for the formation of thin sheets of material to be dried, comprising, in combination with the rotatable drum, 50 partitions arranged in the longitudinal direction of the drum having narrow transverse slots at short distances apart through which the drying material flows in thin sheets at right angles to the direction in which the heating gases flow through said drum, rings of sheet metal near the mantle 55 of the drum standing transversely to said lifting blades and forming an obstacle to the heating gases near the mantle of the drum and forcing them to flow through the middle part and consequently through the sheets of material. 60

In testimony whereof I affix my signature in presence of two witnesses.

GEORG SAUBER.
